G. J. HANSON.

DOOR HANGER.

APPLICATION FILED FEB. 20, 1917.

1,242,798.

Patented Oct. 9, 1917.

UNITED STATES PATENT OFFICE.

GEHART J. HANSON, OF BUXTON, NORTH DAKOTA.

DOOR-HANGER.

1,242,798.

Specification of Letters Patent.

Patented Oct. 9, 1917.

Application filed February 20, 1917. Serial No. 149,909.

To all whom it may concern:

Be it known that I, GEHART J. HANSON, a citizen of the United States, residing at Buxton, in the county of Traill and State 5 of North Dakota, have invented certain new and useful Improvements in Door-Hangers, of which the following is a specification.

This invention relates to door hangers 10 and more particularly to an improvement in hangers for sliding doors and has as its object to provide a device of this class particularly desirable for use in connection with sliding barn, stable, or freight-car 15 doors and which device will permit of the door being moved bodily outwardly from the structure upon which it is mounted to permit of more ready sliding from open to closed position and vice versa and also 20 to permit of the door being moved bodily inwardly toward the structure so as to close the door opening in the wall of the structure in a manner to exclude snow, rain and wind.

25 The invention further aims to provide a door hanger of the class above mentioned so constructed that the same may be operated to shift the door outwardly and inwardly without any considerable exertion.

30 Another aim of the invention is to provide a hanger of this class which may be readily applied to any ordinary barn, stable, or freight-car door or any similar door without alteration of the door structure and 35 which will also permit of the utilization of a hanger track of the ordinary type employed in hanging such doors.

In the accompanying drawings;

Figure 1 is a front elevation of the hanger 40 embodying the present invention applied to a barn door;

Fig. 2 is a detail vertical sectional view through the hanger, the door being shown in closed position;

45 Fig. 3 is a similar view illustrating the door in open position;

Fig. 4 is a perspective view of one of the hangers removed from the door and the supporting track.

50 In the drawings, the numeral 1 indicates one wall of a barn, stable, freight-car or

other structure having a door opening, indicated by the numeral 2 and the numeral 3 indicates the door which is to be slid into and out of position to close the said opening 2, this door being of any of the ordinary constructions and being supplied with two or more of the hangers embodying the present invention, which hangers are mounted for travel upon a track 4, of the ordinary 55 form, supported by suitable brackets 5 upon the wall of the structure 1 in position to extend above the door opening and beyond one side thereof.

The hanger embodying the present invention comprises two members, one of which is secured to the face of the door 3 and the other member is mounted upon the first-mentioned member for sliding movement with relation thereto and supports the 60 roller which travels upon the track 4, it being understood that two or more of these hangers are mounted upon the door to be supported, preferably one adjacent each upper corner of the door.

The first-mentioned member of the hanger, or in other words, that member which is secured directly to the door, comprises an attaching plate, which is indicated by the numeral 6, and this plate is formed 65 with openings 7 for the passage of screws or other suitable securing elements 8 which serve to secure the member to the face of the door. The plate 6 carries a bracket member which is preferably formed from a sheet 80 metal blank having a vertically disposed portion 9 which is riveted or otherwise secured to the outer face of the plate 6, an intermediate portion 10 which extends upwardly and outwardly at an angle from 90 the face of the said plate, and a portion 11 which extends vertically and in a plane parallel to the portion 9 and to the said plate 6, the portion 11 being located opposite and in spaced relation 95 to the upper end of the said plate 6, as clearly shown in Figs. 2 and 3 of the drawings. For a purpose to be presently explained, two or more rods 12 are arranged in parallel relation and are secured at their 100 ends in the plate 6 near the upper end thereof and in the portion 11 of the bracket mem-

ber, these rods occupying a horizontal plane and being suitably spaced from each other. Also for a purpose to be presently explained, the portion 10 of the bracket is formed with 5 a slot 13 extending longitudinally thereof and with an ear 14 which is preferably formed from the material removed to form the slot 13, the said ear projecting from the underside of the said portion 10.

10 The other member of the hanger, or in other words, that member which supports the roller which travels upon the track 4, is also preferably formed from a sheet metal blank including a vertically disposed body 15 portion 15 which at its upper end has a portion extending horizontally inwardly toward the structure upon which the door is mounted and indicated by the numeral 16, the said portion terminating in a downwardly extending portion 17 spaced from the body portion 15 and occupying a plane parallel thereto. The portion 17 and body portion 15 have secured therein the ends of a spindle 18 upon which is rotatably mounted 25 a grooved roller 19 which travels upon the track 4. The lower end of the body portion 15 of this member of the hanger is bent to extend outwardly in a horizontal plane, as at 20, and the portion 20 terminates in an 30 upstanding portion 21 occupying a vertical plane parallel to the body portion 15. The said body portion 15 and the upstanding portion 21 are formed with openings suitably spaced and proportioned to slidably 35 fit the rods 12. It will now be understood that when the hanger has been positioned with the roller 19 properly engaging the track 4, the door may be moved bodily inwardly or outwardly to occupy the position 40 shown in Fig. 2 or the position shown in Fig. 3 either as may be desired, the rods 12 sliding in a corresponding direction through the openings in the second described member of the hanger. In order that this relative movement of the parts may be accomplished, a shifting means is provided which 45 will now be described. The said means includes an oscillatory rod 24 which is supported at its ends in suitable bearing openings formed in the ears 14 of the hanger members on the door, and it is preferable that each end of the rod be squared, as at 50 25, and a finger 26 is fitted on to each squared end of the rod and held in place by means 55 of a set screw 27. The finger 26 extends upwardly through the slot 13 in the respective door attached member of the hanger and the upper end of the finger works in an opening or short slot 28 formed in the 60 portion 20 of the roller carrying member of the hanger. An arm 29 is fixed at one end upon the rod 24 and to the free end of this arm is secured the upper end of a rod 30 which at its lower end is pivotally

connected, as at 31, to a hand lever 32 65 mounted, as at 33, upon the face of the door 3. This lever 32 is provided at its outer end with a handle portion 34 by means of which the lever may be swung downwardly or upwardly, and a suitable keeper device 35 is 70 mounted upon the said face of the door and serves to hold the lever in either of its positions of adjustment. By reference to Fig. 2 of the drawings it will be understood that when the lever 32 is swung upwardly, as, 75 for example, to the position shown in Fig. 1, the rod 30 will be correspondingly moved and the rod 24 would be rocked so as to swing the fingers 26 outwardly and in its movement of the fingers the lower members 80 of the hangers, or in other words, the members which are secured directly to the door, will be moved inwardly toward the structure upon which the door is mounted, whereby to correspondingly move the door and cause the 85 same to completely close the door opening and thus exclude rain, snow, and wind. On the other hand, when the lever 32 is swung downwardly, a downward pull will be exerted upon the rod 30 and the rod 24 will be 90 rocked so as to swing the fingers 26 inwardly toward the structure and as a result the lower members of the hangers, or in other words, the members which support these fingers, will be moved outwardly from the 95 structure carrying with them the door 3. As a result of such movement of the lever 32 the door will be positioned substantially as shown in Fig. 3 of the drawings and being spaced from the wall of the structure, 100 may be more readily slid into and out of closed position.

In order to prevent the rollers 19 leaving the track 4 the body portion 15 of the upper member of each hanger is provided 105 with a finger 36 which projects inwardly from the said portion beneath the lower edge of the track 4, as clearly shown in Figs. 2 and 3.

Having thus described the invention, what 110 is claimed as new is:

1. In a door hanger, a track supported member having a body portion provided with an outward extension terminating in an upstanding portion, the said upstanding portion and the portion of the member opposite thereto being formed with spaced alined openings, a door attached member having spaced portions, spaced rods extending between the said portions of the door attached member and slidably fitting through the openings in the track supported member, a finger mounted for oscillatory movement upon the second-mentioned member and at its ends engaging a socket in the said extension of the first-mentioned member, and means for rocking the said finger.
2. In a door hanger, a track supported

member having spaced portions formed with spaced alined openings, a door attaching member having spaced portions, spaced rods extending between the spaced portions of the door attaching member and slidably fitting through the said openings in the spaced portions of the track supported mem-

ber, a member mounted for oscillatory movement upon the door attaching member and coacting with a portion of the track supported member, and means for oscillating the said member. 20

In testimony whereof I affix my signature.
GEHART J. HANSON. [L.S.]
